UNITED STATES PATENT OFFICE.

PORt RICO MARSHALL AND HARRY L. GOSS, OF HORTON, KANSAS.

HYPODERMIC-NEEDLE STERILIZER.

1,265,224.

Specification of Letters Patent.

Patented May 7, 1918.

Application filed August 17, 1917. Serial No. 186,767.

To all whom it may concern:

Be it known that we, PORt RICO MARSHALL and HARRY L. Goss, citizens of the United States, residing at Horton, in the county of Brown, State of Kansas, have invented a new and useful Hypodermic-Needle Sterilizer, of which the following is a specification.

The subject of this invention is a sterilizer for hypodermic needles, or like articles, and the objects of the invention are, first, to provide a sterilizer which may be easily carried about by a physician, second, to provide a sterilizer which is quick in its action, third, to provide means for removing the needles from the sterilizer, fourth, to provide a sterilizer with a container therefor and a fuel compartment in the container, fifth, to provide a sterilizer with means for burning fuel in tablet form, sixth, to provide means for burning volatile liquid fuel in the sterilizer, seventh, to provide a simple and efficient sterilizer.

With the foregoing and other objects in view, which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

One practical embodiment of the invention is shown in the accompanying drawings, wherein:—

Fig. 1 is a vertical cross section of a sterilizer constructed in accordance with this invention, the same shown in place in its casing.

Fig. 2 is a perspective view of the sterilizer tank cover.

Fig. 3 is a perspective view of the needle tray.

Fig. 4 is a perspective view of a modified form of fuel burner.

Fig. 5 is a perspective view of the preferred form of fuel burner.

Fig. 6 is a perspective view of the fuel burner support.

Fig. 7 is a vertical longitudinal section of another form of burner for liquid fuel.

Fig. 8 is a side elevation of the sterilizer removed from its casing.

Referring to the drawings by numerals of reference:

The sterilizer, when not in use, is stored in a container 1 of rectangular formation, and provided in its top with an inwardly struck portion 2 defining a longitudinal groove. This groove is closed by a friction cover 3 so as to form a compartment in which the fuel tablets may be stored.

The sterilizer proper consists of a suitable casing 4, here shown rectangular, which is provided in its ends and sides with a plurality of ventilator or draft openings 5, which may be arranged as shown, or in any other suitable way. The casing has a bottom 6 secured therein in any convenient and well known manner, and is provided at one end with an opening adjacent the bottom, for the reception of a drawer or slide 7 constituting a fuel holder support.

The slide or drawer is formed with an upstanding front 8 from which is struck out a tongue 9, which is angled to form a gripping member through which the drawer may be manipulated. The striking out of the tongue 9 leaves a ventilating slot 10, which may be supplemented by the openings 11, if desired. Along the longitudinal edges of the bottom are provided upstanding flanges 12 from a median point on each of which rises a lug 13 which aids in retaining the fuel holder or burner against transverse misplacement. A tongue 14 is struck up from the rear end of the bottom of the slide and is bent as shown to form a catch to engage and detachably secure the rear end of the burner in place.

The material of the top of the casing is bent to form a tank 15 preferably rising above the top which extends longitudinally of the casing. Within this tank, and resting on the bottom thereof is loosely placed a perforated tray 17 the sides of which may be bent, as shown, and which is provided with lugs 18 by which the tray may be lifted from the tank. The tank may be closed by a cover 19 when the container 1 is not used.

The burner or fuel holder, is a metal plate 21 formed with a depending angled end 22 the edge of which is adapted to take into a groove 11, not shown, formed at the junction of the front 8 of the slide 7 with the bottom. This secures the front end of the burner in place. The rear end of the plate 21 also depends for a short distance and is turned outwardly at the edge, as seen at 23, to take into the catch 14. A plurality of depressions 24, here shown as two, are

formed in the plate 21, and the material of the plate within these depressions is split, as shown, to provide proper ventilation for combustion. Fuel tablets, not shown, are placed in these depressions and ignited.

Should it become necessary or desirable for any reason to use a fuel other than the tablets designed for use in this sterilizer, a special burner 25, shown in Fig. 4, is provided. This burner is similar to the one just described except that the depending edges 22' and 23' are longer raising the surface higher from the slide bottom. Instead of the depressions 24, an elongated longitudinal depression 24' is provided. The depressed material is cut to form spaced bars as shown. In this depression cotton may be placed and saturated with alcohol.

The modification shown in Fig. 7 is an alcohol lamp or burner, having a tank or body 26 formed with an opening in its top. The material around the periphery of this opening is bent to slope downwardly and inwardly, as seen at 27, to coöperate with the downwardly and inwardly sloping flange 28 of a friction cover 29. The top 29 is provided with an upstanding frusto-conical burner 30 in which ventilating holes 31 are formed. A wick 32 depends from the burner, in which it is frictionally held, and a friction cap 33 is adapted to seat on the burner when the same is not in use.

In practice the device is operated in the following manner:—The sterilizer is removed from its container, or the tank cover taken off and the needles placed in the tank and resting on the tray. Water sufficient for the purpose is placed in the tank and the cover replaced. The slide is withdrawn and two special fuel tablets taken from the compartment 2, or other container, and placed in the depression 24. These tablets are ignited and the slide pushed in place. The water in the tank will boil in one minute and will continue to boil for three minutes. When the needles are thoroughly sterilized the needle tray may be lifted out. The holes in the tray will allow all water to drain from

the needles. As the special fuel tablets used leave no carbon deposit or ash there is no danger of the sterilizer soiling or smutting articles in the physician's case.

When alcohol is to be used as the fuel, the burner is removed from the slide and either the burner shown in Fig. 4, or the lamp shown in Fig. 8 substituted.

The clips 20 formed on the ends of the needle tray serve to hold the needles in place and permit a needle to be screwed to the syringe without handling the needle.

Having thus described the invention, what is claimed as new and sought by Letters-Patent, is:

1. A sterilizer, comprising a casing, a slide in the casing, a burner in the slide, a tank on the casing, and a perforated needle tray in the tank.

2. A sterilizer, comprising a casing, a slide in the casing, a burner detachably secured to the slide, a tank on the casing, and a perforated needle tray in the tank.

3. A sterilizer, comprising a casing, a slide in the casing, a plate on the slide provided with fuel holding depressions, a tank on the casing, and a cover for the tank.

4. A sterilizer, comprising a casing, a slide in the casing, retaining lugs rising from the sides of the slide, a latch rising from the rear end of the slide, a burner in the slide retained by the lugs and detachably secured by the latch, a tank on the casing and integral therewith, a tray in the tank, and a cover for the tank.

5. A sterilizer, comprising a casing, a burner in the casing, a tank on the casing, a cover for the tank, a container for the casing provided with a groove, and a cover closing the groove to form a compartment.

In testimony that we claim the foregoing as our own, we have hereto affixed our signatures in the presence of two witnesses:

PORt RICO MARSHALL.
HARRY L. GOSS.
